(57) **CLAIM**

The ornamental design for network device having wide viewing angle indicators for performance, as shown and described.

DESCRIPTION

This application is related to the following co-pending application, which has assigned to the Assignee of the present invention.

Application Ser. No. 12/554,281, assigned to NETGRER, Inc, filed Sep. 4, 2009, entitled “Wide Viewing Angle Indicators for Network Devices.”

FIG. 1 is a front elevational view of a network device having wide viewing angle indicators for performance;

FIG. 2 is a top plan elevational view thereof;

FIG. 3 is a side elevational view thereof;

FIG. 4 is a right side perspective view without a stand thereof;

FIG. 5 is a left side perspective view without a stand thereof;

FIG. 6 is a front perspective view without a stand thereof; and,

FIG. 7 is a perspective view with a stand in vertical view thereof.
